UNITED STATES PATENT OFFICE.

ROBERT PIERCE, OF LYNN, MASSACHUSETTS, ASSIGNOR OF ONE-HALF
TO FRANK E. BRICKFORD, OF SWAMPSCOTT, MASSACHUSETTS.

LAST.

No. 830,168.

Specification of Letters Patent.

Patented Sept. 4, 1906.

Application filed April 20, 1906. Serial No. 312,886.

To all whom it may concern:

Be it known that I, ROBERT PIERCE, of Lynn, county of Essex, State of Massachusetts, have invented an Improvement in 5 Lasts, of which the following description, in connection with the accompanying drawings, is a specification, like characters on the drawings representing like parts.

In the manufacture of shoes one of the chief expenses is the cost of making new lasts to accord with the styles as they change from season to season. These changes in style are principally in the shape of the toe portion or fore part of the last, practically no change 15 usually being made in the portion of the last back of the ball.

The object of my invention is to produce a simple form of connection for a two-part last which will hold the toe part rigidly on the heel part, so that the last may serve the same purpose as one that is solid and so that said parts will not become disconnected with ordinary usage, although they may be readily disconnected, if desired, thereby enabling the 25 continued use of the heel part from season to season and rendering it necessary only for the different forms of toe parts to be substituted one for another as the styles change.

Figure 1 is a plan view of the ball portion 30 of a last provided with my invention with the top removed. Fig. 2 is a central section on the line 2 2 of Fig. 1. Fig. 3 is an elevation of the rear end of the fore part. Fig. 4 is a horizontal section on the line 3 3 of Fig. 2. Fig. 5 is an elevation of the front end of the heel part. Fig. 6 is a sectional view similar to Fig. 2, showing the manner of disconnecting the parts.

In the drawings a form of three-part last is 40 shown, said parts comprising the heel part *a* and the toe part *b*, the plane of severance therebetween being at the widest part of the fore part or at about the middle of the ball, and the ordinary instep-block *c*, which extends across said plane of severance, as shown in Fig. 2.

A metal plate *d* is rigidly secured by screws to the severed end of heel part *a*, said plate having therein a tapering dovetail 50 groove *d'*, which extends upward from and has its widest end at the bottom of the last. A metal plate *e* is likewise rigidly secured to

the severed end of the toe part, said plate being provided with a correspondingly-tapering dovetail tongue *e'*, which is adapted to enter and become tightly wedged in the dovetail groove *d'* when the two sections are in their proper relations. The meeting faces of the fore part and heel part are recessed from top to bottom to receive the plates *d* and *e*, so that 55 the latter are flush with said faces. A recess *f'* is formed in the fore part directly in the rear of the middle part of plate *e*, and a spring-pressed bolt is located in said recess, the protruding end of said bolt extending 60 through a hole *e*² in said plate in which it is fitted and slidably mounted, said bolt being provided with a collar *f'*, which is adapted to engage the inner side of said plate to form a stop and limit its outward movement. Said 65 bolt *f* normally extends a short distance beyond the side of the plate *d* or its tongue *d'* and is adapted to be pushed back flush with said side. A hole *d*² of corresponding size and location to the hole *e*² is formed through 70 plate *d*, so that when the tongue *e'* is tightly wedged in the groove *d'* and the parts *a* and *b* are in their normal relative positions said bolt will enter and fit in the hole *d*² and will prevent any relative sliding movement of said 75 tongue in said groove and hold the parts securely together. A recess *a'* is formed in the heel part *a* directly in the rear of plate *d*, said recess extending from the instep-block seat down to the inner end of aperture *d*², so that 80 any suitable implement, as that indicated at *j*, may be readily passed down into said recess *e'* into engagement with the end of said bolt *f*, (see Fig. 6,) whereby the latter may be pushed back out of engagement with the 85 plate *d* and the fore part may be slipped down out of engagement with the heel part. In attaching the fore part to the heel part it 90 is simply necessary to press in the bolt *f* so that it is flush with the side of the tongue *e'* and then to slip the tongue *e'* of the fore part up into the slot *d'* until the bolt *f* springs into aperture *d*². The instep-block *c* is held in place by any convenient or well-known means and when in position covers the recess 95 *a'*, although it may be removed without in any way interfering with the connection with the heel and fore part, so that the latter are rigidly held together under all conditions of

ordinary use and there is no reasonable possibility of their becoming detached accidentally.

It will be apparent from the foregoing that 5 one fore part may be readily changed for another without difficulty, so that the heel part may be used indefinitely.

While the bolt *f* is shown in the fore part, it is practically immaterial whether it is located in the fore part or the heel part, so far as the facility of disconnecting the parts and the rigidity with which they are connected is concerned.

The metal plates *d* and *e* when used as 15 above specified are highly advantageous, as they not only enable the parts to be held with great rigidity, so that there will be no side play or rocking motion therebetween even after extended use, but also render it possible 20 to lock these parts rigidly together by means of the bolt *f*, which will continue to fit tightly in said plates even after long continued use. The plate *d* also provides a convenient means for providing an engaging means for the bolt 25 *f* in front of the recess *a'*, through which the tool *j* is passed to disconnect the parts.

Having thus described my invention, what I claim as new, and desire to secure by Letters Patent, is—

A last having the fore part detachably connected to the heel part, each having a metal plate rigidly mounted thereon at the line of severance, said plates being respectively provided with a coöperating dovetail tongue and groove, a spring-actuated bolt located in one 30 of said parts, said bolt being slidably fitted in and movable through the plate thereof, and the other plate having an aperture therethrough into which said bolt is adapted to fit when said parts are in their normal position, 35 to lock them together, said part bearing the apertured plate having a recess therein leading to the inner end of its said aperture, substantially as described.

In testimony whereof I have signed my 40 name to this specification in the presence of two subscribing witnesses.

ROBERT PIERCE.
